(57) **CLAIM**

The ornamental design for a lighting electronics box, as shown and described.

DESCRIPTION

FIG. 1 is a bottom isometric view of a lighting electronics box showing my new design;

FIG. 2 is a top isometric view of the lighting electronics box of FIG. 1;

FIG. 3 is a front view of the lighting electronics box of FIG. 1;

FIG. 4 is a rear view of the lighting electronics box of FIG. 1;

FIG. 5 is a left side view of the lighting electronics box of FIG. 1;

FIG. 6 is a right side view of the lighting electronics box of FIG. 1;

FIG. 7 is a bottom plan view of the lighting electronics box of FIG. 1;

FIG. 8 is a top plan view of the lighting electronics box of FIG. 1; and,

FIG. 9 is a bottom isometric view of a detail of the lighting electronics box of FIG. 1.
